UNITED STATES PATENT OFFICE.

WILFRED SYKES, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL SYSTEM.

Application filed July 7, 1920. Serial No. 394,550.

To all whom it may concern:

Be it known that I, WILFRED SYKES, a citizen of the United States, and a resident of Wilkinsburg, in the county of Allegheny 5 and State of Pennsylvania, have invented a new and useful Improvement in Control Systems, of which the following is a specification.

My invention relates to systems of control and it has special relation to control equipments for reversing rolling mills and the like.

At the present time, the passes of the metal in a reversing rolling mill are manually controlled in the following manner. The main-roll motor speed is initially made sufficiently low to cause the steel to enter the rolls very slowly, in order that the operator may be assured that the billet is properly aligned and located squarely in the groove in the rolls and also for the purpose of avoiding heavy shocks on the mill. The operator then actuates his controller to another position to accelerate the main-roll 20 motor and pass the metal rapidly through the mill. Just before the end of the piece goes through the rolls, the operator again actuates his controller to slow down the main-roll motor and cause the steel to leave the mill slowly. Such procedure requires a skillful operator who must very closely watch the work in order to obtain satisfactory results.

It is the object of my invention, therefore, 35 to render the operation of a reversing rolling mill more nearly automatic than obtains at the present time, in order to increase the output and decrease the labor cost, while producing more satisfactory operation than is possible under present conditions.

Viewed from another angle, the object of my invention is to render the speed of the main-roll motor dependent upon the position, or responsive to the weight, of the 45 metal under treatment, whereby the speed of the motor is automatically increased as the metal reaches the rolls and is automatically decreased just as it leaves the roll.

More specifically stated, one object of my 50 invention is to provide a table-roller device which may, for example, be depressed during the passage of the metal under treatment to close a set of contact members, whereby the main-motor speed is increased.

Other objects of my invention will become 55 evident from the following detailed description, taken in conjunction with the accompanying drawings, wherein—

Figure 1 is a view, in side elevation, of a reversing rolling mill constructed in accordance with my present invention;

Fig. 2 is a simplified outline view of the various rolls.

Fig. 3 is a fragmentary view, partially in section and partially in end elevation, of a 65 portion of the structure that is shown in Fig. 1;

Fig. 4 is a diagrammatic view of the main and auxiliary circuits of a system of control, operating in accordance with my invention;

Fig. 5 is a sequence chart, of well-known form, for indicating the preferred order of operation of the various switches that are 70 shown in Fig. 4; and

Fig. 6 is a diagrammatic view of a modification or extension of my invention.

Referring to Figs. 1 to 3 of the drawing, the structure here shown comprises a reversing rolling mill 1 having the usual stands 80 or end-supports 2 for the main rolls 3 and 4 and which is also provided with the familiar feeding rolls 5 and 6. A plurality of table-rollers 7 are located on each side of the main rolls, in accordance with the usual 85 custom, being driven through the agency of a plurality of bevel gear-wheels 8 which are mounted upon common shafts 9 and 9a for each side of the mill. These shafts are driven, through the agency of reducing gear-trains 10 and 11, by the table-roller motors 12 and 13, respectively.

The main-roll motor or reversing motor 14 is suitably connected to the main rolls, as by a pinion and gear-wheel 15. Consequently, the movements or passes of a billet 16, or other metal under treatment, may be controlled, in both direction and speed, by the table-roller motors when the billet is at some distance from the main rolls and by 100 the main motor 14 when the billet actually reaches the main rolls 3 and 4.

In addition to the customary table rollers 7, a novel table-roller 20 is located preferably close to the feeding roll 5 for a special 105 speed-regulating purpose. It will be noted that the roll 20 is normally located in a position slightly higher than that of the table-

rollers 7, as clearly shown in Fig. 2. The roller 20 is journaled or supported, at its ends, in a block or bearing member 21 which is adapted to slide vertically within a stationary bracket or pedestal 22, being biased to the illustrated upper or out-of-alinement position by means of a suitable helical spring 23, the lower end of which rests upon a bracket or arm 24 forming a part of, or 10 suitably secured to, the main frame-work of the table-roller structure.

A plurality of spaced contact members 25, 26 and 27 are mounted upon a common conducting member that is suitably secured to, 15 and insulated from, the sliding block 21. A corresponding number of stationary contact members 28, 29 and 30, which are respectively disposed below and in alinement with the movable contact members 25, 26 20 and 27, are mounted upon an insulating member which is suitably supported by, or fastened to, the bracket arm 24.

Consequently, depression of the table-roller 20, in opposition to the action of the 25 biasing spring 23, by the traveling billet, or other metal under treatment, causes the electrical contact of the various illustrated contact members 25 to 30, inclusive, for control purposes to be set forth later.

30 A similar depressible roller structure 31 is provided upon the opposite side of the main rolls 3 and 4 in a position corresponding to that of the other depressible roller 20. It will be understood that the depressible rollers 20 and 31, which are located on the opposite sides of the main rolls, respectively correspond to forward and to reverse operation of the mill, only one of them being effective for any given direction of operation.

40 Fig. 2, in addition to the normal relative location of the various rolls 3, 4, 7, 20 and 31, illustrates a slight modification that is necessary in the customary side-guards that travel across the table-rollers. These guards 45 are indicated by the rectangular figures to which the reference characters 35 and 36 are applied, and it will be noted that a small curved notch or groove 37 is provided in the side-guard 35 just above the depressible roller 20, while a corresponding groove 38 is provided in the other side-guard 36 just above the depressible roller 31. Consequently, the normal operation of the side-guards 50 is not interfered with in any way by reason of the normal out-of-alinement position of the depressible table-rollers 20 and 31.

55 Referring to the diagram of Fig. 4, the system here shown comprises a main generator 50 which is connected in permanent series relation with the main or reversing motor 14, a constant-potential exciter 52 being provided for energizing the single shunt field winding 61 of the generator 50 and also a shunt field winding 63 for the reversing 60 motor 14, while a variable-potential ex-

citer 53 is employed to energize a "variable-potential" field winding 62 for the reversing motor 14.

A plurality of reversing switches or contactors 41 and 42 are adapted to be alternately employed for reversing the direction of current in generator field winding 61, and corresponding switches 43 and 44 are utilized for a similar purpose in connection with the motor field winding 62.

75 A normally open switch or contactor 45 is adapted, when closed, to short-circuit a portion of a resistor 55 that is included in circuit with the armature of the constant-potential exciter 52, while a pair of normally closed switches 46 and 47 are adapted to shunt or short-circuit a portion of the resistors 56 and 57, respectively, that are connected in circuit with the main motor field winding 63 and the variable-potential exciter 85 armature 53, respectively.

80 In actual practice, the single contactors 45, 46 and 47 will each preferably be replaced by a plurality of progressively operating switches, in accordance with a familiar practice. However, for the sake of 85 simplicity, the single contactors are shown and will be sufficient to properly set forth the principles of my invention.

90 For effecting the initial or primary control of the various machines, a master switch 58 is provided, being adapted to assume a plurality of operative positions *a* and *b* in the direction designated as "Forward" and *a'* and *b'* in the direction designated as 95 "Reversed."

95 It will be noted that the various contact members that are controlled by the depressible rollers 20 and 31 are connected in circuit with the actuating coils for the resistor-varying switches 45, 46 and 47, as subsequently described in detail.

100 Assuming that it is desired to effect forward operation of the main or reversing motor 14, the table-roller motors 12 and 13 having also been started into operation, the master switch 58 may be actuated to its initial position *b*, for example, corresponding to the previously-mentioned automatic 105 adjustable-speed control. If the controller is actuated to its position *a* only, then a permanently slow-speed operation will be obtained, irrespective of the position of the billet or other metal under treatment, since the contact-closing action of the depressible 110 roller 20 or 31 does not become effective unless the master switch 58 occupies its position *b*.

115 Under this condition, one circuit is established from the positive terminal designated by the character "+" of the constant-potential exciter 52, through conductor 65, actuating coil of the switch or contactor 41, conductor 66, and control fingers 67 and 68, 120 which are bridged by contact segment 69 of 125 130

the master switch 58, to negative conductor 70, which is connected to the negative terminal of the constant-potential exciter 52, as indicated by the character “—”.

5 A corresponding auxiliary circuit is concurrently established from the positive terminal in question, through conductor 71, actuating coil of the switch or contactor 43, conductor 72 and control finger 73, to the 10 contact segment 69 of the master switch.

The two switches or contactors 41 and 43 are thus closed, while switches 46 and 47 are normally closed, as indicated in the first forward position of the sequence chart, Fig. 5.

20 The closure of the switch 41 establishes a new circuit from the positive terminal of the constant-potential exciter 52, through conductors 74, the entire resistor 55, since the switch 45 is normally opened, conductors 75 and 76, lower movable contact member 77 of the contactor 41, conductor 78, field winding 61 of the generator 50, conductors 79 and 80, upper movable contact member 81 of the contactor 41, and conductor 82 to the negative terminal of the constant-potential exciter 52. In this way, the field winding 61 for the generator is built up to the desired value and in the proper direction for 30 effecting forward operation of the main motor 14.

Another circuit is concurrently established from the positive conductor 74, through conductor 83, normally closed switch 46, a portion 35 of the resistor 56, conductor 84, shunt field winding 63 of the main motor 14 and conductor 85, to the negative terminal of the exciter 52. The field winding 63 is thus energized at a relatively strong value by reason of the short-circuit of a large portion of the resistor 56 by the switch 46.

40 The closure of the contactor 43 establishes a circuit, from the positive terminal of the variable-potential exciter 53 through conductor 86, contactor 47, a portion of the resistor 57, conductors 87 and 88, upper movable contact member 89 of the contactor 43, conductors 90 and 91, field winding 62 of the main motor 14, conductors 92 and 93, lower 50 movable contact member 94 of the contactor 43 and conductors 95 and 96, to the negative terminal of the variable-potential exciter 53. The field winding 62 is thus also energized at a relatively strong value by reason of the 55 short-circuit of a large portion of the resistor 57 by the contactor 47.

However, in position *b* of the master switch, if either compressible roller is actuated to its lower position, the contactor 45 is closed, while the contactors 46 and 47 are opened, as indicated. These control operations occur as follows, being dependent upon the position or responsive to the weight of the billet 16 or metal under treatment, as 60 registered by the downward movement of

the one or the other compressible rollers 20 or 31. From the positive conductor 74, one new circuit is established through conductor 105, actuating coil of the contactor 45, conductor 106, lower or stationary contact member 30 that is associated with the compressible roller 20, corresponding upper or movable contact member 27, conductors 109 and 110 and control finger 111, which is connected to the contact segment 69 of the master 75 switch 58.

In this way, the contactor 45 is closed as soon as the billet 16 or other metal to be treated reaches the compressible roller 20 and actuates it to its lower or circuit-closing 80 position. By reason of the closure of the switch 45, a portion of the resistor 55 is short-circuited to increase the current in the generator field winding 61 which, in turn, causes the impression of a higher voltage 85 upon the armature of the main motor 14. Thus, the main motor will accelerate to a new voltage-balancing speed corresponding to the increased voltage upon its armature terminals. However, further speed increases of the main motor 14 are brought about by the weakening of the shunt fields 62 and 63, as about to be described.

Another new circuit is established from the positive terminal of the exciter 52 90 through auxiliary contact member 112 of the switch 45, in its closed position, conductor 112a, actuating coil of the contactor 46, conductor 113, stationary contact member 28 and movable contact member 25, that are 100 associated with the compressible roller 20, whence circuit is completed through conductor 109 to the negative terminal, as previously traced. The contactor 46 is thus lifted to insert the entire resistor 56 in circuit with 105 the shunt field winding 63 of the main motor. The electrical interlocking of the switches 46 and 47 with the switch 45 prevents loss of motor torque by weakening of its field flux before the generator voltage has 110 been reduced. Such weakening of the field strength imparts an increased speed to the motor armature, in accordance with familiar principles.

At the same time, another circuit is established from the conductor 112a, through conductor 116, actuating coil of the contactor 47, conductor 117, stationary contact member 29 and corresponding movable contact member 26, that are associated with 120 the compressible roller 20, and thence through conductor 109, as already set forth. In this way, the contactor 47 is lifted to insert the entire resistor 57 in circuit with the “variable-potential” field winding 62 for the 125 main motor 14, thus weakening the exciting strength thereof in approximate proportion to the weakening of the shunt field winding 63.

All three of the control operations just 130

described, namely, the increase in the strength of the generator field winding 61 and the decreases in the exciting values of the motor field windings 62 and 63, tend to increase the speed of the main motor, as already mentioned, these actions being initiated as the front end of the billet 16 reaches and depresses the roller 20. However, the inherent time-element in the main motor 14, before full-speed conditions are actually attained, is such as to bring about the desired speed approximately just after the front end of the billet has entered the main rolls 3 and 4. It will be appreciated that the design of the motor 14, with regard to the distance between the depressible roller 20 and the main rolls 3 and 4, may readily be made such as to provide the desired time-element in the motor operation.

20 The roller 20 is, of course, depressed throughout the passage of the billet 16, thus automatically providing the desired high speed as the billet passes through the mill. As soon as the rear end of the billet passes 25 beyond the depressible roller, the roller springs back to its normal or contact-opening position and, consequently, the switch 45 is opened and the switches 46 and 47 are closed, as illustrated in Fig. 4, causing the motor 14 to slow down to the desired speed approximately at the time that the rear end of the billet leaves the main rolls 3 and 4.

In this way, control of the main motor 35 speed is automatically obtained in accordance with the presence and position of the material to be treated, the only operation that it is necessary for the operator to perform being the simple throw of a controller 40 lever to its final position.

It will be understood that, upon the actuation of the master switch 58 to its final reverse position *b'*, the main motor 14 is operated in the reverse direction in a similar 45 manner to that hereinbefore set forth, to cause a reverse pass of the metal through the mill.

For example, a circuit is established from the positive conductor 65 through actuating 50 coil of the switch 42, conductor 121 and control finger 122 to the contact segment 123 of the master switch 58. Furthermore, another circuit is established from the positive conductor 71 through the actuating coil 55 of the contactor 44, conductor 124 and control finger 125 to the contact segment 123.

The field winding 61 for the generator 50 and the field winding 62 for the motor are thus reversed, as will be understood without 60 detailed tracing of the circuits.

Since the control finger 111a is engaged by the contact segment 123 in position *b'* of the master switch 58, the conductors 110a, 106, 113 and 117 are energized whenever the 65 depressible roller 31 is actuated by the

traveling billet. A plurality of lower or stationary contact members 107, 118 and 114, are adapted to engage corresponding movable contact members 108, 119 and 115 which correspond to the previously- 70 described movable contact members 25, 26 and 27. Consequently, the closure of the contactor 45 and the opening of the contactors 46 and 47 occur whenever the roller 31 is depressed to provide the desired high- 75 speed conditions of the main motor 14 at the proper time, as hereinbefore set forth.

Referring to Fig. 6, the system here shown involves an extension of the automatic idea previously explained, whereby 80 the operation of the main motor may be considered as entirely automatic, since its direction of rotation is automatically governed in accordance with the direction of rotation of the table-rollers.

Fig. 6 shows one method of obtaining this type of control, the master switch 58 for the main motor 14 and a master switch or controller 128 for the table-roller motors 12 and 13 being located side-by-side.

The power for the table-roller motors 12 and 13 is provided in any suitable manner, as from a distribution circuit including conductors 129 and 130, the remainder of the illustrated system comprising the motor 12, 90 an accelerating resistor 132 therefor, a set of reversing contactors or switches 133 to 136, inclusive, a plurality of resistor contactors or switches 137 and 138, and a line contactor 139.

The motor 12 preferably comprises a commutator-type armature 141, a series field winding 142, a commutating field winding 143 and a shunt field winding 144, which is bridged by the familiar field-discharge resistor 145.

The direction, as well as the degree of energization of the motor 12, is governed by the master switch or controller 128, which may be of any well-known form. In practice, the master switch 128 usually comprises a pair of mechanically-coupled face-plate controllers, assembled back-to-back, for governing the operation of the respective table-roller motors 12 and 13. However, for the sake of simplicity, a drum controller has been illustrated having two sections respectively corresponding to the motors 12 and 13.

The complete control for the motor 12 120 only is shown. Since the control of the corresponding motor 13 is similar in all respects, it is not deemed necessary to illustrate such circuits. Furthermore, since the particular type of control of the table-roller 125 motors forms no essential part of my present invention, I do not deem it necessary to describe the operation thereof in detail. It will be sufficient to state that the controller 128 comprises a contact segment 147, corre- 130

sponding to forward operation of the motor 12, and a contact segment 148, corresponding to reverse operation thereof, these contact members being adapted to engage a 5 plurality of control fingers 149 in a suitable sequence, in accordance with a familiar practice.

Corresponding contact segments 150 and 151 and control fingers 152 are provided for 10 governing the operation of the other table-roller motor 13, as will be understood.

To ensure the proper co-ordinate operation of the master switches 58 and 128 for the main roller motor and the table-roller 15 motors, respectively, the apparatus is arranged as follows. The switches are equipped with the usual controlling handles 154 and 155 and are further provided with suitable sprockets 157 and 158, for example, 20 which may be rigidly attached to the operating shafts 159 and 160 of the respective controllers. A chain 161, or the like, passes around the two sprockets 157 and 158, whereby the desired concurrent operation of 25 both switches, by moving, for example, the one handle 155 for the table-roller controller 128, is ensured.

The gear ratio between the two controller shafts is, of course, determined by the relative size of the sprockets and is preferably such that each controller reaches its final position at approximately the same time. In other words, the operation of the table-roller motors to full speed in either direction causes the master switch 58 to automatically occupy the one or the other of its final positions δ or δ' .

Consequently, the main motor travels at the initial or slow-speed rate until the billet 40 or metal under treatment passes over the one or the other of the depressible rollers 20 and 31.

It will be understood that the particular type of depressible roller construction may 45 be varied to suit operating conditions and that various other equivalent devices may be employed in lieu thereof, if desired. For example, in the case of plate mills, it might be well to provide a roller that is supported 50 on an arm which is mounted upon the upper roll shaft of the plate mill. This roller would be arranged to fall between two of the table rollers so that metal reaching it would lift it up slightly to make the necessary electrical contacts, in accordance with the previous description.

Furthermore, it will be understood that, if desired, more than one step of automatically-varied control may be obtained by providing 60 more than one depressible roller upon each side of the main rollers, whereby different values of field-circuit resistance are cut into or out of circuit, as desired. Consequently, I do not wish to be restricted to the specific 65 structural details, circuit connections or ar-

rangement of parts herein set forth, as various modifications thereof may be effected within the spirit and scope of my invention. I desire, therefore, that only such limitations shall be imposed as are indicated in the appended claims.

I claim as my invention:

1. In a control system for rolling mills, the combination with a motor for driving the rolls for rolling the metal under treatment, of means dependent upon the position of one end of said metal for varying the speed of said motor.

2. In a control system for rolling mills, the combination with a motor for driving the rolls for rolling the metal under treatment, of means engaged by one end of the traveling metal for increasing the motor speed as the metal enters the rolls.

3. In a control system for rolling mills, the combination with a motor for driving the rolls for rolling the metal under treatment, of means responsive to the weight of said metal for increasing the motor speed as the metal enters and decreasing the motor speed as the metal leaves the rolls.

4. In a control system for rolling mills, the combination with a motor for driving the rolls for rolling the metal under treatment, of a device adapted to be actuated in opposite directions as the respective ends of the metal approach the mill for varying the motor speed.

5. In a control system for rolling mills, the combination with a motor for driving the rolls for rolling the metal under treatment, of a contact-making device adapted to be depressed and lifted as the respective ends of the metal approach the mill for varying the motor speed.

6. In a control system for rolling mills, the combination with a motor for driving the rolls for rolling the metal under treatment, of a shiftable table-roller for governing the operation of said motor.

7. In a control system for rolling mills, the combination with a motor for driving the rolls for rolling the metal under treatment, of a depressible table-roller for increasing the motor speed as the metal enters the rolls.

8. In a control system for rolling mills, the combination with a motor for driving the rolls for rolling the metal under treatment, of a bodily movable table-roller, and a circuit closed upon actuation thereof for governing the motor operation.

9. In a control system for rolling mills, the combination with a motor for driving the rolls for rolling the metal under treatment, of a depressible table-roller, and a circuit closed upon actuation thereof for increasing the motor speed.

10. In a control system for rolling mills, the combination with a motor for driving

- the rolls for rolling the metal under treatment, of a depressible table-roller for controlling the excitation of said motor and spaced from said rolls such a distance that
- 5 the time element required for the work to proceed from the depressible roller to the rolls will be sufficient to change the motor speed by a predetermined amount.
11. In a control system for rolling mills, 10 the combination with a motor for driving the rolls for rolling the metal under treatment, of means engaged by the traveling metal for controlling the operation of said motor and spaced from said rolls such a distance that the time element required for the work to proceed from said means to the rolls will be sufficient to increase the motor speed by a predetermined amount.
12. In a control system for rolling mills, 20 the combination with a motor for driving the rolls for rolling the metal under treatment, said motor having a shunt field winding, of a table-roller normally out of alignment with the remaining table-rollers, and 25 switching means closed by movement of said roller to the aligned position for reducing the strength of said field winding.
13. In a control system for rolling mills, 30 the combination with a motor for driving the rolls for rolling the metal under treatment, and a table-roller motor, of means for
- ensuring the operation of the main rolls and of the table-rollers in the same direction, and means dependent upon the position of the metal for varying the operation of 35 one of said motors.
14. In a control system for rolling mills, 40 the combination with a motor for driving the rolls for rolling the metal under treatment, and a table-roller motor, of interlocked control means for effecting operation of the main rolls and of the table-rollers in the same direction, and means engaged by the traveling metal for varying the operation of the main-roll motor.
15. In a control system for rolling mills, 45 the combination with a motor for driving the rolls for rolling the metal under treatment, and a table-roller motor, of a plurality of controllers for governing the respective 50 motors, a single operating handle for effecting movement of both controllers to the respective final positions, corresponding to slow-speed operation of the main-roll motor, and a depressible table-roller for increasing the main-roll motor speed as the metal enters the rolls.

In testimony whereof, I have hereunto subscribed my name this 22nd day of June, 1920.

WILFRED SYKES.
